7 Claims. (Cl. 128—536)

ABSTRACT OF THE DISCLOSURE

A girdle construction in which the lower edge is provided with a double thickness of stretch material (preferably two-way stretch) of substantial vertical width and extending around the entire, or almost the entire, bottom edge of the girdle to form a zone which firmly grips the wearer's body without cutting or creasing it and anchors the girdle against tendencies to "ride up."

This invention relates to a girdle construction and particularly to the provision of a special feature therein, adaptable for use with any girdle which exhibits, on certain wearers, a tendency to "ride up," said special feature being adapted to overcome such tendencies.

In the present advanced state of development of this art the basic problems of figure control may be regarded as satisfactorily solved—for most figures—by garments of various designs, differing in countless details including the arrangement of "panels," the distribution of one-way and two-way stretch areas, the outline of the top and bottom edges, etc. It is still true, however, that an otherwise satisfactory girdle, especially when worn without garters, will ride up and require constant downward adjustment. To attempt to solve this by simply increasing the tension around the bottom edge frequently causes irritation, discomfort and marking of the flesh with unsightly welts.

It is the object of the present invention to provide a structure which has the effect of increased tension without any of the disadvantages, this comprising specifically a double band of horizontal-stretch or, more particularly, two-way stretch material combined with or constituting at least a substantial portion of the lower edge of the girdle or the entire lower edge thereof.

Practical embodiments of the invention are shown in the drawing, wherein:

FIG. 1 represents a front elevational view of a girdle, laid flat and unstretched;

FIG. 2 represents a back view of the same girdle;

FIG. 3 represents a detail vertical section on the line III—III of FIG. 1;

FIG. 4 represents a detail vertical section on the line IV—IV of FIG. 1;

FIG. 5 is an alternate embodiment representing a front elevational view of a girdle, laid flat and unstretched;

FIG. 6 represents a back view of the girdle shown in FIG. 5;

FIG. 7 represents a detail vertical section on the line VII—VII of FIG. 5;

FIGS. 8 and 9 represent detail vertical sections, similar to FIG. 7, but showing further alternate embodiments.

Referring to the drawings, FIG. 1 shows a girdle having a main section 10 running completely around the back and terminating in the front where it is joined to a front panel 12 by the stitching 14. The front panel 12, which may be formed of two separate panels joined by the stitching 16, is stretchable in a vertical direction and resists stretch in a horizontal direction. Alternatively, the front panel 12 may be made of nonelastic material. The main section 10, on the other hand, is stretchable in a horizontal direction or in both a vertical and horizontal direc-

2

tion. The front panel 12 is full length while the main section 10 is shortened at its lower end as illustrated.

In order to resist the tendency for the girdle to "ride up" on the user, a double band, indicated generally at 18, 5 is affixed to the lower edge of the girdle. As shown in the drawings, the double band 18, secured to the main section 10 by the stitching 20, 30 extends from one side of the front panel 12 around the back and terminates adjacent the other side of the front panel 12 where it is affixed thereto by the stitching 22. As indicated on the drawings, the double band 18 is made from a piece of horizontally and vertically stretchable material which is folded back on itself at 24 (FIG. 3) to define an inside and outside band 26 and 28, respectively. Alternatively, 15 the double band 18 may be made of material stretchable only in a horizontal direction. As shown in FIG. 3, the upper edge of the outside band 28 is stitched to the outside of the main section 10 at 20 while the upper edge of the inside band 26 is stitched to the inside of the main section 10 at 30. Since, as will be hereinafter described, it is the double band 18 and its location at the lower edge of the garment which prevents "riding up," it will be understood that the specific double band arrangement in FIG. 3 is not critical and that various other ways of forming the double band may be employed. 20 Some of these alternate arrangements will be described in detail in connection with FIGS. 8 and 9.

"Riding up" of the girdle on the user is often caused by stretching and increase in the circumference at the 30 lower edge of the girdle. According to the present invention, the double band 18 at the lower edge of the girdle functions to increase the resistance to stretching at this critical area. In comparing single and double bands of the same width, it will be evident that the double band 35 requires more tension or applied force to stretch while at the same time, because of the double thickness, the elastic restraining force is distributed over a greater total cross sectional area of band material to thereby diminish the concentration thereof on the user. Thus, with a double band, the greater force required to stretch it will reduce the tendency for the girdle to "ride up." Also, since the force is distributed on overlapping bands, the outer band reinforces the inner band in a manner to limit the elastic restraining force applied to the user.

The front panel 12 of FIG. 1 may have its lower edge doubled over and stitched at 32 as shown in FIG. 4 to increase the strength of the front panel and prevent curling or bunching up. Also the back of the main section 10 may have a reinforcing panel 34 stitched in place as 40 shown in FIG. 2. The reinforcing panel may be of varied shape or material, either elastic or nonelastic. Alternatively, the reinforcing panel 34 may be dispensed with. A vertical panel (similar to the front panel 12) may be used at the rear of the garment. Thus, the rear would look 45 like the front as illustrated in FIG. 1 wherein both front and rear vertical panels extend to the bottom edge of the garment where they are joined at the lower side portions by two double bands of horizontal or two-way stretch material, one on either side of the garment extending from the front to the rear panel. This latter arrangement has 55 been found to be quite comfortable to the user. The front and rear panels may be of vertical stretch or they may be nonelastic.

In the alternate embodiment of FIGS. 5—7, a front 60 panel, rear panel, and reinforcing back panel are not used. The main section 35 of the girdle is formed as an endless tubular sheet of horizontal stretch or two-way stretch material. The double band 18a, which is stretchable in a horizontal direction but resists stretching in a vertical direction, is formed as an endless band and is affixed to the lower edge of the main section 35 by the stitching 36.

As shown in FIG. 7, the double band is formed by doubling over a piece of material and fitting the edge of the main body 35 between the edges of the double band, the three edges being stitched together as shown at 36. Alternatively, the double band 18a may be two-way stretchable as in the FIG. 1 embodiment.

In FIG. 8 the double band 18b is stitched at 37 and 38 to the inside of the lower end portion of the main body 35b to form what is, in effect, a triple band. FIG. 9 is similar to FIG. 8 except that the double band 18c is stitched to the outside of the main section 35c as indicated at 40 and 42.

The circumference of the double band depends on the degree of elasticity which is needed to ensure comfort while preventing any "riding up." The double band may be horizontally and vertically stretchable or just horizontally stretchable. Also it may be made from two pieces instead of a single piece folded over on itself although the preferred forms use a folded strip so that the bottom edge has no seam or hem to press into the skin.

Although several embodiments have been described in detail it will be understood that various modifications and combinations may be employed and also additional features added. Thus, attached or detachable garters may be used on the girdle or a zippered closing may be employed. Various combinations of two-way, one-way, or nonstretch panels along with various types of waist bands may be employed. The front panel 12 may be full length as in FIG. 1 or it may terminate short of the lower edge of the main section with the double band extended below the front panel. As previously mentioned, a rear panel may also be employed and the double band may be superimposed on the rear or front panel (e.g., similar to the arrangement shown in FIGS. 8 and 9). Also only one of the double bands may be superimposed on the front (or rear) panel. The double band may also accommodate the front (or rear) panel similar to the arrangement of FIG. 7.

Velvet elastic may also be employed to prevent rubbing, for example, a strip may be stitched to the front, inside, bottom of the girdle or other locations as desired.

The garment of this invention prevents "riding up" while affording comfort to the user. The arrangement provides for great flexibility of use whereby the invention may be used on various garments and may even be attached to existing garments. Variously arranged panels having different elastic properties may be used on the garment to afford efficacy and comfort in all areas without adversely affecting the applicability of the present invention. Since the garment of this invention does not "ride up," it may be worn without garters thereby making

it attractive to users who desire to go barelegged when tan.

It will be understood that various changes may be made in the form, construction and arrangement of the several parts without departing from the spirit and scope of the invention and hence I do not intend to be limited to the details shown or described herein except as the same are included in the claims or may be required by disclosures of the prior art.

What I claim is:

- 10 1. A garment such as a girdle or the like, comprising a body encircling portion which is at least in part circumferentially elastic, and a separate double band of substantial vertical width which is made of two layers of two-way stretch material affixed to the lower edge of said body encircling portion, the outer layer of said double band reinforcing the inner layer thereof to increase the amount of tension required to circumferentially stretch the double band while distributing the elastic restraining force applied to the user, said double band thereby resisting upward movement of the garment on the user without adversely affecting comfort.
- 15 2. A garment according to claim 1 wherein said double band is a strip of material folded over on itself.
- 20 3. A garment according to claim 1 wherein said double band extends below the terminating lower edge of said body encircling portion.
- 25 4. A garment according to claim 1 wherein lower edge of said body encircling portion is accommodated between the two bands of the double band.
- 30 5. A garment according to claim 1 wherein said double band extends about the complete lower circumference of the garment.
- 35 6. A garment according to claim 1 wherein said double band is superimposed on the inside of the lower end section of said body encircling portion.
- 40 7. A garment according to claim 1 wherein said double band is superimposed on the outside of the lower end section of said body encircling portion.
